DESIGN FOR A COMBINED BACK SCRUBBING CLOTH AND SOAP HOLDER

Albert M. Steichen, West Englewood, N. J.

Application February 6, 1940, Serial No. 90,067

Term of patent 3½ years

To all whom it may concern:

Be it known that I, Albert M. Steichen, a citizen of the United States, residing at West Englewood, Bergen County, State of New Jersey, have invented a new, original, and ornamental Design for a Combined Back Scrubbing Cloth and Soap Holder, of which the following is a specification, reference being had to the accompanying drawing, forming part thereof.

Fig. 1 is a face view of a combined back scrubbing cloth and soap holder, showing my new design;

Fig. 2 is a reverse view of the same;

Fig. 3 is an enlarged cross-sectional view on substantially the plane of line 3—3 of Fig. 1.

I claim:

The ornamental design for a combined back scrubbing cloth and soap holder, substantially as shown.

ALBERT M. STEICHEN.
